CLAIM

The ornamental design for an oral care device as shown and described.

DESCRIPTION

FIG. 1 is a perspective view of an oral care device, embodying the new design;

FIG. 2 is a top view thereof;

FIG. 3 is a right view thereof;

FIG. 4 is a bottom side view thereof;

FIG. 5 is a left side view thereof;

FIG. 6 is a front view thereof; and,

FIG. 7 is a back view thereof.

In the drawings, the evenly-spaced broken lines depict portions of the oral care device that form no part of the claim.
